UNITED STATES PATENT OFFICE.

JOHN F. COLEMAN, OF EVERETT, MASSACHUSETTS.

AUTOMATIC SCRAPING-MACHINE.

No. 821,583.

Specification of Letters Patent.

Patented May 22, 1906.

Application filed April 17, 1905. Serial No. 255,867.

To all whom it may concern:

Be it known that I, JOHN F. COLEMAN, a citizen of the United States, residing at Everett, in the county of Middlesex and State of Massachusetts, have invented a new and useful Automatic Scraping-Machine, of which the following is a specification, reference being made therein to the accompanying drawings.

My invention relates to machines for scraping up snow, gravel, sand, and other similar substances, transporting the same wherever required, and there depositing the load.

The object of my invention is to provide an apparatus whereby snow, gravel, sand, or other similar substance may be scraped up automatically, carried away, and deposited wherever desired, and thereby effect a large saving of the time and labor now expended in loading and unloading carts and other devices employed in removing these substances.

Broadly considered, my device comprises a scraper mounted upon wheels and provided with means whereby the scraper may be lowered for the purpose of loading and then raised and locked and also provided with means whereby the scraper may be unloaded.

The following is a clear description of my invention, reference being made to the accompanying drawings, in which—

Figure 1 is a view in perspective of my machine with the scraper raised and locked. Fig. 2 is a rear view of the machine with the scraper lowered. Fig. 3 is a front view of the same. Fig. 4 is a side elevation of the same. Fig. 5 is a longitudinal sectional view of the same on line 5 5 in Fig. 3. Fig. 6 is a plan view of the scraper, and Fig. 7 is a plan view of my machine.

Similar numbers refer to similar parts throughout the several views.

In the drawings is shown a frame-body mounted upon front wheels 2 2 and rear wheels 3 3, adapting it to be moved over the ground like a wagon. The frame-body consists of two horizontal bars 4 and 5, joined together near their forward ends by a cross-bar 6 and in the rear by two braces 7 and 8, which have downwardly-extending sides provided with slots 9 9, each brace resembling an inverted letter U. In the rear the frame-body rests upon a rear axle 10, which is arched to permit a scraper to be raised, as will hereinafter be explained, and on the axle 10 are mounted the wheels 3 3. A front axle 12, upon which are mounted the wheels

2 2, is pivotally adjusted to the forward cross-bar 6 by means of a king-pin 14 and two angle-braces 15 15. The forward axle 12 is provided with a pole 16 in order that the device may be drawn by horse-power. Also to the cross-bar 6 is fastened a right-angled bar 20, provided with a cross-piece 21, upon which is mounted upon springs 22 22 a seat 23 for the driver; but this is not a material part of my invention, and the driver's seat may be mounted upon the machine in any suitable manner.

Beneath the rear axle 10 and the two braces 7 and 8 is suspended, by means of various connections, a scraper 30, which may be raised or lowered as desired. The scraper 30 is rectangular in form, having sides 31 31 and a tail-board 32; but the forward end 33 is open, and at that point the sides 31 31 flare outwardly for the purposes of gathering in material and protecting the mechanism on the sides of the scraper.

In order that the scraper 30 when filled may be easily unloaded, I provide in the bottom of the scraper a plurality of doors 34 34, so mounted upon rods 35 35 that they may be opened or closed by turning the said rods, and when opened the load is discharged through the bottom of the scraper. To facilitate opening the doors 34 34 when the scraper is loaded, I mount the doors off-center on the rods 35 35 in such a manner that when the doors are opened only a small portion of each door turns upwardly into the material, which arrangement materially decreases the resistance which the load would otherwise offer to the opening of the doors.

For the purpose of opening all the doors simultaneously and by one movement of a lever I extend the rods 35 35 through one side of the scraper 30 and turn them upwardly to form arms 36 36, the rearmost arm being further lengthened into a lever 37, to which the other arms 36 36 are connected by a rod 38. Any movement of the lever 37 causes a similar movement of the arms 36 36, and by pushing the lever 37 in one direction or the other all the doors in the bottom of the scraper are simultaneously opened or closed, as the case may be.

For the purpose of supporting the scraper and raising and lowering it when desired I provide the following means: To the sides 31 31 of the scraper 30 are riveted guides 50 50, provided with studs 51 51 at their upper ends. These studs 51 51 engage and slide in

the slots 9 9 of the braces 7 and 8, and thus permit the scraper to be raised and lowered vertically. In addition thereto I provide two uprights 52 52, one riveted to each side 5 31 of the scraper 30 and each provided with prongs 53 53, which inclose and slide up and down on the vertical side sections of the arched axle 10 as the scraper is raised or lowered. Besides the above supports and guides 10 I provide also levers 60 60, two on each side, the lower end of each being pivotally connected to the side 31 of the scraper 30 by means of a bolt 61 and the upper end of each being pivotally connected to a bell-crank lever 62 by a pin 63. The bell-crank levers 62 62 are pivotally mounted in hangers 64 64, fixed to the frame-beams 4 and 5. On each side of the machine the bell-crank levers 62 62 have their other ends joined by a bar or 15 beam 65 in order to secure a concerted action in the movement of the said bell-crank levers. To each beam or bar 65 is pivotally attached a small arm 66, one of said arms having its other end pivotally connected to a lever 67, fixedly mounted on a shaft 68, which is supported by hangers 69 69 on the frame-beams 4 and 5. The small arm 66 on the other side of the machine has its other end pivotally attached to a lever 70, which is 20 fixedly mounted on the shaft 68. By this arrangement any movement of the lever 67 turns the shaft 68 and the lever 70 and moves all the bell-crank levers 62 62 on both sides of the machine simultaneously. The small 25 arms 66 66 act as flexible connections between the levers 67 and 70 and the bars 65 65 and permit the bell-crank levers 62 62 to swing up or down when the scraper 30 is lowered or raised.

30 In order to support and lock the scraper 30 when it is raised, I provide lock-bars 80 80 on each side of the machine, pivoted on the sides of the braces 7 and 8 at 81, adjacent to the slots 9 9, and having a projection 35 or spur 82 adapted to slide under the stud-bolts 51 51 and support the scraper 30 by means of the guides 50 50. On each side of the machine the upper ends of the pivoted lock-bars 80 80 are connected by rods 83 83 40 in order that the two lock-bars on each side may be moved together. From the forward end of the rod 83 is a short rod 84, connected to a lever-beam 85, which joins the rods 84 84 on both sides, so that any movement of 45 the lever-beam 85 moves all the lock-bars simultaneously. Upon the lever-beam 85 is fixedly mounted a lever-arm 86, which is used to turn the lever-beam and thereby lock or unlock the scraper. If it is desired to 50 operate the locking device from the driver's seat, a rod 87 connects the lever-arm 86 with a bell-crank lever 88, which is hung in the hanger 89 under the driver's seat. The forward end of the bell-crank lever 88 is connected by a rod 90 and a cross-rod 91 to two 55 bars 92 92, mounted at 93 on the cross-bar 6. Beneath the forward ends of the bars 92 92 are interposed coil-springs 94 94 for the purpose of keeping up the lower end of the bell-crank lever 88, and thereby retain the lock-bars 80 80 in a locked position. The free ends of the bars 92 92 are turned downwardly 60 to form catches 95 95, which engage and retain sliding bolts 97 97, mounted on the frame-beams 4 and 5. To the sliding bolts 75 are joined draw-bars 96 96, attached to the forward end of the scraper 30 and serving as additional supports. When the scraper is lowered, the sliding bolts 97 97 are released and slide rearward to the stops 98 98. 80

The operation of my machine is as follows: As shown in Fig. 1, the scraper 30 is in a raised position, and the machine may be drawn from place to place as is a wagon. In order to load, it is necessary to drop the scraper, which result is secured by first releasing the stud-bolts 51 51 from the lock-bars 80 80 and the draw-bars 96 96 from the catches 95 95. This may be done either by the driver pressing the bar 91 down with his foot, which releases the sliding draw-bars 96 96 and through the medium of the bell-crank lever 88 and rod 87, pulls forward the lever 86, and thereby unlocks and releases the stud-bolts 51 51, or it may be done by the operator standing at 90 the side of the machine and throwing forward the lever-arm 86. In either case whether the operating force be applied to the bar 91 or the lever 86 the same parts are set in motion and the same result is obtained. At the same 100 time that the draw-bars 96 96 and the stud-bolts 51 51 are unlocked the lever 67 should be pulled to the rear, which throws the lower ends of the bell-crank levers 62 62 forward and permits the other ends to descend and the scraper falls to the ground of its own weight into the position shown in Figs. 4 and 105 5. While in this position the machine is drawn forward and the scraper 30 scrapes up the material. It is to be noted that the levers 60 60 and the bell-crank levers 62 62 are of such dimensions that when the scraper is upon the ground they lie in a straight line from 61 to 64 and act as additional support to the scraper to withstand the extra strain 110 due to the scraping process. After the scraper 30 has been filled with material it is raised by pushing the lever 67 forward, which turns the shaft 68 and pulls down the forward ends of the bell-crank levers 62 62 through the medium of the lower part of lever 67, lever 70, arms 66 66, and bars 65 65. As the forward ends of the said bell-crank levers are drawn downwardly the other ends 115 thereof are raised, and thereby raise up the scraper 30, which when drawn to the top is locked by pulling the lever-arm 86 to the rear. Provided the springs 94 94 are sufficiently powerful, the lock-bars 80 80 will always be 120 retained in a locked position and the studs 51 130

51, when the scraper is raised, will slide up the forward faces of the lock-bars, press them back until the prongs 82 82 are passed, when the springs 94 94 will cause the lock-bars to fly forward into a locked position. In this event it is unnecessary to pull the lever-arm 86 to the rear, as the device automatically locks itself. With the scraper loaded, raised, and locked the machine may then be drawn 10 like a wagon to any locality and the load deposited merely by pulling the lever 37 to the rear, which opens the doors 34 34 and allows the load to drop through. After the scraper is unloaded the doors are closed by pushing forward the lever 37, and the machine is then in a condition to be loaded again.

The means heretofore described for raising, lowering, locking, and unloading my scraper may be varied in details or other means substituted therefor without departing from the spirit of my invention, and I desire to claim the same in as broad a manner as is legally possible.

What I claim is—

25 1. In a scraping-machine, the combination of a scraper mounted on wheels and provided with means for opening and closing its bottom, means to lower and to raise said scraper, and means to lock said scraper when raised.

30 2. In a scraping-machine, the combination of a suitable frame mounted upon wheels, a scraper hung in said frame and provided with means to open and to close its bottom, means to lower and to raise said scraper, and means to lock said scraper when raised.

35 3. In a scraping-machine, the combination of a suitable frame mounted upon wheels, a scraper provided with guides and adapted to move upwardly and downwardly in said frame, means to unload said scraper through its base, means to lower and to raise said scraper, and means to lock said scraper when raised.

40 4. In a scraping-machine, the combination of a frame mounted upon wheels, a scraper provided with supporting-guides which are in moving engagement with the sides of said frame, means to unload said scraper through its base, means to lower and to raise said scraper, and means to lock said scraper when raised.

45 5. In a scraping-machine, the combination of a frame mounted on wheels, and having depending slotted side braces, a scraper provided with supporting-guides which move in said slotted side braces, means to lower and to raise said scraper, and means to lock said scraper when raised.

55 6. In a scraping-machine, the combination of a frame mounted on wheels and having depending slotted sides, a scraper having supporting-guides which move in the slots in said sides, said scraper being provided with means whereby its base may be opened or closed, means to lower and to raise said

scraper, and means to lock said scraper when raised.

7. In a scraping-machine, the combination of a frame mounted on wheels and having depending slotted side braces, a scraper provided with supporting-guides which move in said slotted side braces, a plurality of bell-crank levers, operatively connected to said scraper to raise and to lower it and means to lock said scraper when raised. 70

8. In a scraping-machine, the combination of a frame mounted on wheels and having depending side braces, a scraper hung on a plurality of bell-crank levers which are pivotally attached to said frame and whereby said scraper may be raised or lowered, means to lock said scraper when raised, and means to unload said scraper through its base. 75

9. In a scraping-machine, the combination of a frame mounted on wheels and having depending side braces, a scraper, provided with supporting-guides engaging said side braces, and hung on bell-crank levers pivotally attached to said frame whereby said scraper may be raised or lowered, means to operate 85 said bell-crank levers, and means to lock said scraper when raised.

10. In a scraping-machine, the combination of a frame mounted on wheels, a scraper hung on bell-crank levers which are pivotally mounted on said frame, said scraper being provided with a bottom which may be opened or closed, means whereby said bell-crank levers may be operated to raise or to lower said scraper and means to lock said 90 scraper when raised. 100

11. In a scraping-machine, the combination of a frame mounted on wheels and having depending side braces, a scraper having a bottom provided with means for opening and closing it, supporting-guides for said scraper engaging said side braces, a plurality of bell-crank levers pivotally mounted on said frame and connected to said scraper, means whereby said bell-crank levers may be operated to 105 raise or to lower said scraper, and means to lock said scraper when raised. 110

12. In a scraping-machine, the combination of a frame mounted on wheels and having depending slotted side braces, a scraper, 115 guides supporting said scraper and in moving engagement with said slotted side braces, bell-crank levers pivotally mounted on said frame and attached to said scraper, means to operate said bell-crank levers to raise or to 120 lower said scraper, and means to lock said scraper when raised.

13. In a scraping-machine, the combination of a frame mounted on wheels and having depending slotted side braces, a scraper provided with means for unloading through 125 its base, guides supporting said scraper and in moving engagement with said slotted side braces, a plurality of bell-crank levers, pivotally mounted on said frame, one end of each 130

being pivotally connected to said scraper, and the other end of each being operatively connected to a lever, said lever to operate said bell-crank levers to raise or to lower said scraper, and means to lock said scraper when raised.

14. In a scraping-machine, the combination of a frame mounted on wheels and having depending slotted side braces, a scraper, guides attached to said scraper and provided at their free ends with studs which move in the slots in said side braces, a plurality of bell-crank levers pivotally mounted on said frame one end of each being pivotally connected to said scraper and the other end of each being operatively connected to a lever, said lever to operate said bell-crank levers to raise or to lower said scraper, lock-bars pivotally mounted on said side braces and adapted to engage said guide-studs to lock said scraper in a raised position, and a lever operatively connected to said lock-bars to operate the same.

15. In a scraping-machine, the combina-

tion of a frame mounted on wheels and having depending slotted side braces, a scraper provided with means for unloading through its base, guides attached to said scraper and provided at their free ends with studs which move in the slots in said side braces, a plurality of bell-crank levers pivotally mounted on said frame, one end of each being pivotally connected to said scraper and the other end of each being operatively connected to a lever, said lever to operate said bell-crank levers to raise or to lower said scraper, lock-bars pivotally mounted on said side braces and adapted to engage said guide-studs to lock said scraper in a raised position, and a lever operatively connected to said lock-bars to operate the same.

In testimony whereof I have hereunto set my hand, in the presence of two subscribing witnesses, this the 10th day of March, 1905.

JOHN F. COLEMAN.
